UNITED STATES PATENT OFFICE.

JOHN ERICKSON, OF CHICAGO, ILLINOIS, ASSIGNOR TO AUTOMATIC ELECTRIC COMPANY, OF CHICAGO, ILLINOIS, A CORPORATION OF ILLINOIS.

SUBSTATION TELEPHONE SET.

1,373,607.

Specification of Letters Patent.

Patented Apr. 5, 1921.

Application filed November 10, 1916. Serial No. 130,528.

To all whom it may concern:

Be it known that I, JOHN ERICKSON, a citizen of the United States of America, and a resident of Chicago, county of Cook, and

5 State of Illinois, have invented certain new and useful Improvements in Substation Telephone Sets, of which the following is a specification.

10 My invention relates in general to substation telephone sets but is concerned more particularly with telephone sets for use in automatic party line systems. In systems of the above general character a considerable problem has been the prevention of interference between subscribers on the same line. Various lock-out systems have been proposed and used to a certain extent but they all have the disadvantage of excessively complicating the substation apparatus, which is 15 very objectionable in any case, and particularly so in the case of substation equipment for use on rural lines. Again, the subscribers themselves usually view with disfavor any attempt to restrict their free use of the 20 telephone, as is done in lock-out systems, even though aware that a better service might result therefrom.

25 In view of these considerations, I prefer not to use any positive lock-out device, but 30 to trust rather to a sense of courtesy on the part of the subscribers; and in accordance with this idea, I so design the substations that the subscribers thereat are enabled to listen in on the line to observe its idle or 35 busy condition without interfering with a call that may be in progress at the time. Being thus severally charged with responsibility for the service, the subscribers will seldom deliberately or maliciously interfere 40 with each other.

45 In attaining the foregoing objects, I employ a simple mechanical device associated with the receiver hook at each substation, together with suitable circuits; all of which 50 will be described and explained fully hereinafter, reference being had to the accompanying drawings.

55 In the drawings, Figure 1 shows my invention applied to a wall type telephone, Figs. 2 and 2^A show a modification of the invention applied to a desk type telephone, while Fig. 3 is a circuit diagram applicable either to Fig. 1 or to Fig. 2.

55 Referring now to Fig. 1, a sectional portion of the box of a wall telephone is indicated by the reference character 2. A

bracket 3, on the inside, and an escutcheon plate 4, on the outside, are mounted on the box by means of machine screws 5 and 6. A right-angled piece 10 is pivotally mounted 60 on the bracket 3 by means of the pin 9. The bracket 3 is double, as is also the piece 10, they both being formed from symmetrical flat punchings, and the latter fits closely within the sides of the bracket. The detachable receiver hook H is clamped between the two sides of the pivoted piece 10 by means of the screw 11. It will be observed that the end of the hook is slotted so that when the screw 11 is loosened it can be removed. The 65 contact springs 20—24, inclusive, are mounted on a downwardly extending portion of the bracket 3 and are controlled by the receiver hook, the piece 10 being provided with a roller which engages the 70 spring 23.

The lever 7 is a stamping U section, like the bracket 3, and is pivoted on the receiver hook by a rivet 8. The lower end of the lever 7 is held away from the side of the box by 80 a spring 13, whereby the projection 12, at the upper end, is enabled to engage the top of the slot in the escutcheon plate 4.

Reference will now be had to the circuit diagram Fig. 3 for an explanation of the 85 operation. The line conductors 25 and 26 are assumed to extend to the exchange and terminate there in an individual switch in the usual and well known manner. It is to be understood also that a plurality of substations similar to the one shown in Fig. 3 are connected in bridge of the line conductors, but since the substations are all alike, but one of them has been shown.

When the receiver is on the hook the contact springs 23 and 24 are together, as seen in Fig. 3, and the ringer K is connected in bridge of the line as follows: line conductor 25, condenser C, contact springs 23 and 24, and the ringer K to line conductor 26. 100 When the receiver is taken off the hook to initiate a call, the hook is raised by the spring 23 until the projection 12 engages the top of the slot in the escutcheon plate 4. In this position of the hook, the listening 105 position, the contact springs 23 and 24 are separated and the former is in engagement with the contact spring 22, as shown clearly in Fig. 1. A circuit including the receiver R may now be traced over the following 110 path: line conductor 25, condenser C, contact springs 23 and 22, secondary winding

S of the induction coil, receiver R, and the calling device springs I to the line conductor 26. The calling subscriber is now supposed to listen in his receiver to see whether or 5 not the line is in use. Since the receiver R is bridged across the line conductors in series with the condenser C and since the transmitter circuit is still open, another subscriber who is making a call or who is engaged in 10 conversation will not be interfered with.

Assuming the line to be idle, the subscriber will now push in on the lower end of the lever 7, thereby disengaging the projection 12 from the slot in the escutcheon plate 15 4 and permitting the receiver hook to rise to its final position. The four contact springs 20—23, inclusive, are now in engagement, with the result that the condenser C in the receiver circuit is short-circuited and 20 the transmitter circuit is closed as follows: positive pole of battery B, contact springs 21 and 22, transmitter T, and the primary winding P of the induction coil to the negative pole of battery B. The substation is 25 now in condition for talking.

Connection is extended to the called line by manipulating the calling device CD which may be of the general type of calling device disclosed in the British patent to C. 30 G. S. Dicker, No. 29654 of 1910. Calling devices, or impulse senders, as they are sometimes termed, of the foregoing general type are well understood and need not be described in detail. It may be mentioned, however, 35 that the calling device is preferably provided with a pair of shunt springs X, closed as soon as the dial is moved from its normal position, whereby the impulse springs I may be included in a direct bridge 40 of the line conductors.

I will now explain a modified form of the invention, reference being had to Figs. 2 and 2^A. Fig. 2 shows a vertical section of a desk telephone which comprises essentially a tubular stand 30, mounted on a base 31, and supporting at its upper extremity a transmitter head 32. Fig. 2^A is a horizontal section of the transmitter head taken on the line Z. To proceed, the lower cylindrical portion 45 of the head 32 fits inside the tubular stand 30 and has a vertical hole 33 and a transverse slot 34 to provide room for the receiver hook H' and its accessories. The hook H' is pivoted at 35 in an obvious manner and controls the contact springs 20—24, 50 inclusive, by means of the rod 37. A finger lever 39 is attached to the end of the hook by the pivot 40 and projects through a slot in the tubular stand 30. A cross piece 36 55 closes the transverse slot 34 in the head 32 at a point slightly below the downwardly projecting end 41 of the finger lever 39.

In the drawing the receiver hook is shown in its normal position, it being assumed 60 that the receiver is hung up. When

the receiver is removed, the hook is raised by the spring 42, carried on the rod 37 at the lower end thereof. As the right hand end of the hook moves downward under the influence of the spring 42, the finger 70 lever 39 is caused to rotate about the pivot 40 by the spring 38 so that the projecting end 41 is brought directly above the cross piece 36. As soon then as the projection engages the cross piece 36 the upward 75 movement of the receiver hook is stopped. In this intermediate position the contact springs 23 and 24 are separated and the former contact spring engages the contact spring 22. After listening in his receiver 80 and finding the line to be idle, the subscriber will now press down on the finger lever 39, thereby disengaging the projection 41 from the cross piece 36. The receiver hook is thus permitted to rise the 85 rest of the way to close the contact springs 20—23, inclusive, whereby the receiver and transmitter circuits are closed for talking.

Having described my invention what I consider to be new and desire to have protected by Letters Patent will be pointed out in the appended claims.

What I claim as my invention is:

1. In a telephone system, a substation telephone set having ringing, talking, and listening circuits, a switch hook and contact springs controlled thereby, a condenser, said hook effective in one position to close said ringing circuit including said condenser, in another position to close said talking circuit and to short circuit said condenser and in an intermediate position to close said listening circuit including said condenser, and a device effective when the receiver is removed to stop said hook in its intermediate position.

2. In a substation telephone set, a pair of line conductors, a hook switch, a bridge of said conductors including a signal, closed when the receiver is on the hook, means for stopping the hook switch in an intermediate position when the receiver is removed, a second bridge closed in the intermediate position of the hook and including a condenser and a receiver, means for permitting the said hook to pass its intermediate position, and means for then short-circuiting said condenser.

3. In a substation telephone set, a switch hook having upper, lower, and intermediate positions, a circuit including a signal and a condenser closed in the lower position of said hook, a second circuit including a receiver and said condenser closed in the intermediate position, and a shunt circuit for said condenser closed in the upper position.

4. In a substation telephone set, a hook switch having normal, off normal, and intermediate positions, transmitter and re-

- ceiver circuits open in the normal position of said switch, means for closing a receiver circuit in the intermediate position of said switch and for closing said transmitter circuit and closing a new receiver circuit only in its off normal position, and a pawl pivoted to said hook for automatically stopping the same in its intermediate position when the receiver is removed.
10. 5. In a substation telephone set, a hook switch having normal, off normal, and intermediate positions, transmitter and receiver circuits open in the normal position of said switch, means for closing a receiver circuit in the intermediate position of said switch and for closing said transmitter circuit and closing a new receiver circuit only in its off normal position, and a trigger mounted on said hook and co-operating with a fixed stop to retain said hook in its intermediate position.
15. 6. In a substation telephone set, the combination with a hook switch, of a listening circuit, and a talking circuit controlled by said hook switch, said hook switch having three positions, means for moving said hook switch from first to second position to close said listening circuit and for moving said switch hook from second to third position to render said listening circuit inoperative and to close said talking circuit.
20. 7. In a substation telephone set, the combination with a hook switch of a signaling circuit, a listening circuit, and a talking circuit controlled by said hook switch, said hook switch having three positions, said signaling circuit closed when the hook switch is in first position, means for moving said switch hook from first to second position to open said signaling circuit and close said listening circuit, and for moving said hook switch from second to third position to render said listening circuit inoperative and to close said talking circuit.
25. 8. In a substation telephone set, the combination with talking and listening circuits, and a hook switch for controlling the same, automatic means for stopping said hook switch in intermediate position when the receiver is removed, said listening circuit closed when the switch is in intermediate position, and means for moving said hook switch from intermediate to off normal position to render said listening circuit inoperative and close said talking circuit.
30. 9. In a substation telephone set, the combination with talking, signaling and listening circuits, and a hook switch for controlling the same, automatic means for stopping said hook switch in intermediate position when the receiver is removed, said signaling circuit closed only in normal position of said hook switch, said listening circuit closed when the switch is in intermediate position, and means for moving said
- hook switch from intermediate to off normal position to render said listening circuit inoperative and close said talking circuit.
10. In a substation telephone set, a hook switch having normal, off normal and intermediate positions, transmitter and receiver circuits, open in normal position of said switch, means for closing a receiver circuit in intermediate position of the switch and for closing the transmitter circuit and a new receiver circuit only in its off normal position, a support on one end of said hook switch for holding said receiver, a lever pivoted to the opposite end of said switch hook, and a fixed stop in the path of said lever for holding the hook switch in intermediate position.
15. The combination of an escutcheon, a telephone switch - hook extending therethrough and pivoted at one end, a pawl on said switch-hook for engaging said escutcheon whereby the switch-hook may be held in intermediate position, and means for further raising the switch-hook when the pawl is pressed out of engagement with the escutcheon.
20. 11. The combination of an escutcheon, a telephone switch - hook extending therethrough and pivoted at one end, a pawl on said switch-hook for engaging said escutcheon whereby the switch-hook may be held in intermediate position, means for further raising the switch - hook when the call is pressed out of engagement with the escutcheon, a line circuit associated with said switch-hook, a calling device for sending impulses over said line and a switch controlled by said switch-hook, whereby when the switch-hook is in intermediate position the calling device is inoperative for sending impulses over the line and when the switch-hook is in said further raised position the calling device is operatively connected to the line.
25. 12. The combination of an escutcheon, a telephone switch - hook extending therethrough and pivoted at one end, a pawl on said switch-hook for engaging said escutcheon whereby the switch-hook may be held in intermediate position, means for further raising the switch - hook when the call is pressed out of engagement with the escutcheon, a line circuit associated with said switch-hook, a calling device for sending impulses over said line and when the switch-hook is in intermediate position the calling device is inoperative for sending impulses over the line and when the switch-hook is in said further raised position the calling device is operatively connected to the line.
30. 13. A subscriber's telephone set in combination with a telephone line, a condenser, an impulse sender in said set for sending a series of impulses over said line, a switch-hook, an automatic device for holding the switch in intermediate position when the receiver is removed and means for further raising the switch-hook thereafter, a switch controlled by said switch - hook whereby said impulse sender is rendered inoperative for sending impulses over said line when the switch-hook is in intermediate position by having said condenser included in series therewith, and for operatively connecting the impulse sender to the line and short circuiting said condenser when the switch-hook is further raised.
35. Signed by me at Chicago, Cook county, State of Illinois, this 4th day of Nov., 1916.

JOHN ERICKSON,
